UNITED STATES PATENT OFFICE.

SAMUEL G. McMEEN, OF SAN FRANCISCO, CALIFORNIA, ASSIGNOR TO McMEEN & MILLER, OF CHICAGO, ILLINOIS, A COPARTNERSHIP.

TELEPHONE-RECEIVER.

1,027,494.

Specification of Letters Patent. Patented May 28, 1912.

Application filed April 28, 1910. Serial No. 558,238.

To all whom it may concern:

Be it known that I, SAMUEL G. McMEEN, a citizen of the United States of America, and a resident of San Francisco, county of San Francisco, and State of California, have invented a new and useful Improvement in Telephone-receivers, of which the following is a specification.

My invention pertains to telephone receivers, and particularly to receivers for use in common battery or centralized energy systems.

In such systems, in order that the substitution apparatus may be of the simplest type, it is convenient to permit the current which flows upon the telephone line during conversation to flow through the telephone receiver as well. This is objectionable when the receiver is of the ordinary construction, and many devices, comprising in nearly all cases apparatus and circuit wiring external to the receiver itself, have been devised, and some of them have been used successfully, to prevent the undesirable effects produced by the current flowing through the receiver.

In some of these devices, direct current is prevented from flowing through the receiver, and in others it is greatly reduced.

An element in the construction of the usual type of receiver is the permanent magnet. This in my improved receiver I replace by an electromagnet.

In order that the direct current of the telephone line may flow through the receiver, and that the simplified circuits possible under such a condition may be used, I make a receiver having a speech-current translating coil and having an electromagnetic field coil, and I then provide means within the receiver case for separating the currents of the telephone line into direct currents, the path of which includes the field magnet coil; and speech currents, the path of which includes the diaphragm-actuating or speech-current translating coil.

In the drawings which accompany and form a part of this specification—Figure 1 shows a sectional elevation through my improved receiver; Fig. 2 shows an enlarged section of the upper part of my receiver; Fig. 3 shows a plan view of the under side of the magnetic devices; Fig. 4 shows diagrammatically the circuit arrangement;

Fig. 5 shows diagrammatically an alternative form of my device, using one coil instead of two.

Like figures refer to like parts throughout the several views.

The receiver case is composed of three parts—body 1, end piece 2 and cap 3. Within body 1, which may be a casting or a turned piece, is an annular internal rib 1'. A rolled condenser 4 is rolled upon a fiber tube 5, thus making a tubular condenser. This condenser is inserted into the receiver case from the small end, and is clamped by the end piece 2, which is screwed down upon it, thus holding it securely in place. The terminals of the condenser are arranged upon the end nearer the large end of the receiver.

The electromagnetic system of the receiver comprises a pressed magnetic cup, two helices contained thereby, a magnetic core, a magnetic washer and a magnetic diaphragm. Terminals are mounted upon the exterior of the magnetic cup, and the coils, core and washer are mounted within the cup, the diaphragm being placed over the mouth thereof, and both cup and diaphragm clamped between parts 1 and 3 of the receiver, all as shown clearly in the drawings. Coil 6 is the field coil of the receiver, which produces that constant magnetism required to place the diaphragm under an initial stress. The magnetic washer 7, together with the smaller cylinder 8 of the magnetic cup, form a magnetic circuit very nearly closed, and give a very high inductance value to the coil 6, and at the same time produce the required magnetism at the upper end of the core 9. The dimensions of washer 7 may be such as to permit the desired initial magnetic strength at the upper end of the core 9. Thus, the initial magnetic strength may be controlled in the design and manufacture.

The coil 18 is the actuating coil of the device and is made of flat form and located in close proximity to the diaphragm, so that the majority of its magnetic lines of force will pass through the diaphragm. Upon the back of the cup is mounted the insulating block 10 upon which are the terminals 11, 12 and 13, which serve as a means for connecting the coils and condenser in circuit, as

shown in Fig. 4. One terminal of coil 6 is brought out through the cup 8 and soldered to the terminal 11; one terminal of the condenser 4 is connected to terminal 11; while one terminal of coil 18 is led through the magnetic cup and connected to the terminal 13, the remaining terminal of condenser 4 being also connected to terminal 13; and the remaining terminals of coils 18 and 6 are led through the cup 8 and connected to terminal 12. The circuits of the device are clearly shown in Fig. 4. The incoming conductors 20 and 21 of the receiver pass through the receiver in two paths, the first of which includes only the field winding 6 in the shape of a long, slender cylinder about the core, and the second of which includes condenser 4 and the winding 18 in the form of a very short cylinder of comparatively large diameter.

Because of the fact that the winding 6 is relatively narrow and is in a path carrying direct currents, some of the lines of force generated by the current through that winding will close through the magnetic washer 7 and some will close through the center of the diaphragm, but in general it is intended that the magnetic circuit of the winding 6 is not formed wholly through the diaphragm.

The winding 18 carries speech currents, and this winding is made relatively thin, so that the diaphragm and the bottom of the shallow portion of the cup are separated by but a small distance, thus not concentrating the forces at the center of the diaphragm. With such a construction, even if the central core were to be removed, there would remain a tendency for the two sides of the magnetic circuit so described to draw together under the influence of any current, other magnetic conditions being absent; and while the center of the diaphragm is free to move and is under the influence of a greater force to make it move, there is such a tendency in some degree, throughout the area occupied by the winding 18.

In all forms of telephone receivers which have come into general commercial use, the diaphragm is influenced at or near its center only, whether there be both or only one of the poles presented to that portion of it. While my present invention does concentrate the forces at about the center of the diaphragm, it is not confined in its action to that concentration.

In the present state of the art of telephone receiving devices, the requirement is not so much for improvement which shall make the telephone receiver more powerful in translating powerful currents, but which shall make it more sensitive for currents received over long distances. But in receiving voice currents over long distances, those which are most attenuated and most distorted are those which were of the higher

frequencies and lower amplitudes. While it is of importance that transmission lines be so constructed as to reduce the losses due to attenuation and distortion, it is also important so to construct the receiving device as to be responsive to what remains of the currents of higher frequency, after they have been subject to such losses as have occurred in the line.

A relation exists between a diameter of the receiver diaphragm and the frequency of voice current to which the receiver is most readily responsive. While, therefore, my drawing shows in scale a diaphragm of two inches or more in diameter and a cup of similar size, I do not consider it essential that so great diameters be used. Satisfactory commercial results are secured by diaphragm and cup diameters of the order of one inch. Such a modification of the general magnitude of these parts should be accompanied by a similar modification in the shell of the winding 6, so that the winding 6 may, in general, be long and narrow, while the winding 18 may, in general, be wide and thin.

Fig. 5 illustrates an alternative form of my device, in which a permanent magnet is utilized instead of an electromagnet, and direct currents are prevented from passing through the actuating coil by means of the condenser 4' retained within the handle of the receiver, as described in the foregoing specification, the condenser in this form of my device being of the same general shape and characteristics as described.

Having thus described my invention, what I claim as new and desire to secure by United States Letters Patent is—

1. In a telephone receiver, a case of three parts; an internal annular rib upon the body part of said case; a condenser between said rib and the second of said parts, forming a cap upon one end of the receiver; and an electromagnetic system clamped between said receiver body and the third of said parts, forming a cap upon the other end of the receiver.

2. In a telephone receiver, a removable end cap; an internal abutment member; and a condenser within the receiver, and retained by said cap and said abutment member.

3. In a telephone receiver, a case; a tubular condenser within said case; an electromagnetic system within said case; and a flexible conducting cord passing through the middle of said condenser and connecting to said electromagnetic system and to said condenser.

4. In a telephone receiver, a case; a magnetic cup; a diaphragm closing the mouth of said cup; a helix within said cup; a condenser within said case, and connected electrically with said helix.

5. In a telephone receiver, a magnetic cup in the shape of two coaxial cylindrical chambers; a magnetic diaphragm closing the mouth of said cup; a magnetic core in the 5 axis of said cup; and a washer upon said core, located at or near the division plane of said two coaxial cylindrical chambers.

Signed by me at San Francisco, county of San Francisco and State of California, in the presence of two witnesses.

SAMUEL G. McMEEN.
